[57] CLAIM

The ornamental design for a telephone base and stand, as shown and described.

DESCRIPTION

FIG. 1 is a front elevational view from a lower side of the telephone base and stand showing my new design;

FIG. 2 is a bottom view of the telephone base and stand;

FIG. 3 is a front elevational view from an upper side of the telephone base and stand;

FIG. 4 is a bottom view of the telephone base and stand;

FIG. 5 is a left-hand side view of the telephone base and stand;

FIG. 6 is a right-hand side view of the telephone base and stand; and,

FIG. 7 is a front elevational view of the telephone base and stand.

The broken line showings in FIGS. 1, 2, 3, 4, 6 and 7 are for illustrative purposes only and form no part of the claimed design.
